UNITED STATES PATENT OFFICE.

JOHN L. L. KROOK, OF CAMBRIDGE, MASSACHUSETTS.

AUTOMATIC GAS SHUT-OFF.

SPECIFICATION forming part of Letters Patent No. 734,718, dated July 28, 1903.

Application filed October 6, 1902. Serial No. 126,036. (No model.)

To all whom it may concern:

Be it known that I, JOHN L. L. KROOK, a citizen of the United States, residing at Cambridge, in the county of Middlesex and State 5 of Massachusetts, have invented a new and useful Improvement in Automatic Gas Shut-Offs, of which the following is a full, clear, and exact description, reference being had to the accompanying drawings, forming a 10 part of this specification, in explaining its nature.

My invention relates to an automatic gas shut-off whereby a supply of gas is automatically turned off after its flame is extinguished. 15 The special object of my invention is to provide in case of an accidental extinguishment of the flame or when the flame is extinguished in any other way than by turning off the gas by the local valve, which controls 20 its passage to the burner; and it consists in such adaptation and correlation of parts that this valve would be closed after the flame is extinguished by atmospheric pressure. The means by which this effect is obtained, together 25 with the adaptation shown in the combination and organization of the various parts, can best be seen by reference to the drawings, where—

Figure 1 shows a gas-burner provided with 30 my device, the same being shown partly in elevation and partly in cross vertical section. Fig. 2 shows a horizontal cross-section on the line 2 2 of Fig. 1.

Referring to the drawings, A represents a 35 gas-burner, which may be of any kind, shape, or size. The burner is shown as having a mantle a; but this is in no way essential to the perfection of my invention apart from showing its capabilities, as will hereinafter appear. 40 a' represents the gas-supply pipe, while a² represents a pipe-section interposed between the supply-pipe and the burner, which it serves to connect. This pipe-section a² makes screw connection with the parts to which it 45 is secured in order that it may be a detachable part, and the threads by which the screw connections are made are preferably cut to a gage, by which the section may be readily attached to any kind of gas burner or fixture. 50 Extending through the section a² is the central gas-passage a³. This passage is closed

by a valve which takes the form of a sliding stem a⁴, which has placement to extend when closed crosswise the passage. The inner end of the valvular stem extends into a slight recess a⁵, formed in the wall of the interior passage-way, this to more effectually prevent the flow of gas. The valvular stem a⁴ is fitted to slide easily, but still so as to prevent a leakage of the gas, and on this account it is 55 better to provide the wall of the pipe-section, through which the stem extends, with a boss a⁶, in which there is formed a stuffing-box a⁷ of any common form or structure, as shown. Upon the outer end of the stem is formed a 60 knob or head a⁸, by which the stem may be moved in or out by hand as its valve-forming end moves crosswise or clear from the passage-way, which it is adapted to close.

Extending from the side of the interposed section a², and preferably with an integral attachment, is the bracket a⁹, which supports the chambered section B. This section B is made a detachable member by means of a screw connection with its supporting-bracket, 75 and it is preferably held to extend so that the cylindrical passage b, formed in said chamber, may lie approximately in line with the valvular stem a⁴ and so that the piston or plunger b' contained in said passage may 80 make as direct an attachment with the valvular stem as possible. It does this by means of its piston-rod b² and the strap-arms b³ secured thereto, which turn around the pipe-section a² on opposite sides and make connection with the valvular stem a⁴ near its outer end, approximately as indicated. By 85 this method of connection any motion given to the piston would be correspondingly and simultaneously reproduced in the sliding valve. In other words, the piston b', if properly actuated, would draw the valvular stem across to a closed placement and so shut off the flow of the gas to the burner. In this connection the looped formation of the arms 90 b³ is to be noted, which permits of their lateral movement relative to the pipe-section a²; also, the grooves or recesses b⁴, formed in the adjacent walls of the pipe-section, in which the arms lie as they turn around the sides 95 thereof. By recessing the arms thus they are 100 guided in their movement and added stability

is given to the sliding parts which they serve to connect—namely, the piston and the valvular stem.

The section B is left open at its inner end or at the end of its cylindrical passage b, so that the atmosphere may have access to the piston. It is best provided with a dust-guard b⁵ at this point, however. Through the upper wall of the piece forward the piston is cut an opening or port b⁶, which is closed by the ball-valve b⁷, normally occupying by gravity the hollow segmental seat b⁸. In order that there may be no danger of this valve becoming displaced, it has, as shown, a cage b⁹.

15 The valvular opening b⁶, it is to be noted, is cut forward of the piston b', but so that when the piston is moved forward in its cylinder-chamber b and the valvular stem a⁴ is drawn to a closed placement, as shown in Fig. 20 1, then the edge of the piston will contact with the valve and lift it from its valve-seat.

The end of the section b forms a chamber b¹⁰, narrowing to form an outlet b¹¹, through which connection is made to the globular air-chamber C by suitable pipe connections c. The pipe c may make any suitable joint connection with the forward end of the section B; but the section is preferably disposed to make its connection with an upturned end 30 against which the end of the pipe c abuts. The outside of this turned end is screw-threaded. Then by the coupling c' clamping against an annular flange formed on the end of the pipe c and screwing down upon the 35 threaded end of the upturned section aforesaid a separable joint is obtained.

The air-chamber C is made preferably globular in shape, as represented, and its placement is such that it will receive the heat of 40 the gas-flame. This is best done by placing the chamber directly over the flame, when it will be subjected to the direct influence of its heat. The chamber may be provided with a hood C', which is made to partake of the 45 nature of an ornamental fixture. It also helps retain and conserve the heat from the flame.

The upturned pipe carrying the air-chamber may be stayed in any way necessary. I have shown a single stay c², which would 50 apparently meet all requirements.

It is to be noted in the examination of these parts just described that the air-chamber C and its connecting passages, inclusive of the chamber b¹⁰, are practically closed to the atmosphere with the exception of the opening or port b⁶, and this normally remaining closed by the valve b⁷.

The operation of my device is as follows: Assuming the valve a⁴ controlling the gas- 60 passage to be drawn out and the gas lighted, the heat of the flame acting upon the air inside the globular chamber would cause the same to expand and a portion of the air by the force of expansion would be forced down 65 through the pipe connection c into the chamber b¹⁰ of the interposed section B and then

out through the valve through the port b⁶, the valve b⁷ controlling the port being raised by the force of outward expulsion of the air. This would continue as long as the gas was 70 lighted or until the action of the heat from the flame would cause no further expansion and so consequent expulsion of the air. Assuming now the gas to be accidentally extinguished, with the valvular stem controlling 75 the gas - passage left open, as soon as the heat of the flame was removed from the air-chamber the air remaining in the chamber from that which had previously been expelled by the heat of its expansion would begin to 80 cool. As it cooled it would contract and with the contraction a partial vacuum would be formed, for the valve b⁷, which controls the only passage to the outer air, would become closed by gravity just as soon as the air con- 85 fined in the globular chamber and its connecting passages ceased to be outwardly expelled by its heat expansion; besides the outward air acting upon the vacuum or partial vacuum formed in the globular chamber and 90 its connecting passages would act upon this valve and force it closed. As the air in the chamber continued to cool and contract, a more perfect vacuum of course would be induced, until at length the pressure of the 95 outer air acting upon this vacuum would be sufficient to move or push forward the piston b', which would simultaneously with its movement draw the valvular stem to a closed placement and the gas would be turned off. 100

Of course it would be necessary that the air-chamber and its connecting passages should be supplied with air after this movement of the piston in order that its operation may be continued when the gas is again lighted and 105 subsequently extinguished. I have made provision for this by the contacting of the piston, after it has performed its function, against the valve b⁷, which controls the port b⁶. The valve is raised by the piston, whereupon the outer air rushes in and supplies the air-chamber and its connecting passages. 110

My device is entirely automatic, requiring no especial manipulations in order for the various parts to perform their proper functions, for just as soon as the valve controlling the gas-passage is opened the parts are set, as it were, and ready to operate. 115

It is obvious, considering the method of operation, that various changes may be made 120 in the construction and organization of the various parts without departing from the spirit of my invention. For example, the valve which controls the supply of gas to the burner may take other forms apart from that 125 shown by the sliding stem. In fact, any means adapted to shut off the supply of gas to the burner and to be actuated by the piston might be used. Likewise other means may be resorted to to relieve the pressure of 130 air within said air-chamber as the same becomes heated, or changes may be made in the

operating means to be acted upon by the pressure of the atmosphere and still be within the essence of my invention.

Having thus fully described my invention, I claim and desire to secure by Letters Patent of the United States—

1. In an automatic gas shut-off the combination with a gas-burner of a valve for controlling the supply of gas to the flame, an air-chamber having placement to be influenced by the heat of the flame, an air-valve for the admission or escape of air, a connection between the said air-valve and said chamber, a movable member, a connection between said movable member and said gas-controlling valve, the movable member aforesaid being so placed that one side thereof is exposed to the pressure within said air-chamber and the other side to that of the atmosphere, substantially as and for the purposes set forth.
2. In an automatic gas shut-off, the combination with a gas-burner of a valve for controlling the supply of gas to the flame, an air-chamber having placement to be influenced by the heat of the flame, an outwardly-opening valve, a connection between said outwardly-opening valve and said air-chamber so as to permit of the escape of air there-through, a piston, a connection between said piston and said gas-controlling valve, the said piston being so placed as to close a passage from the interior of said chamber to the atmosphere whereby one side of said piston is exposed to the pressure within said chamber and the other side to the atmosphere, substantially as and for the purposes set forth.
3. In an automatic gas shut-off, the combination with a gas-burner of a valve for controlling the supply of gas to the flame, an air-chamber having placement to be influenced by the heat of the flame, an interposed chamber, a connection between said interposed chamber and the air-chamber aforesaid, a movable member, a connection between said movable member and the gas-controlling

valve aforesaid, the said valve being so combined with said interposed chamber as to close an otherwise open side thereto, whereby one side of said movable member is exposed to the pressure within said air-chamber and the other side to that of the atmosphere and an air-valve permitting of the admission to and escape of air from said air-chamber.

4. In an automatic gas shut-off, the combination with a gas-burner of a valve for controlling the supply of gas to the flame, an air-chamber having placement to be influenced by the heat of the flame, an interposed chamber, a connection between said interposed chamber and said air-chamber, a piston carried by said interposed chamber and so disposed as to be acted upon by atmospheric pressure, means for connecting said piston with the gas-controlling valve, and an outwardly-opening air-valve in said interposed chamber, the said valve being so disposed that it will be automatically opened by the piston when in a certain position, substantially as and for the purposes set forth.

5. In an automatic gas shut-off, the combination with a gas-burner of a valve for controlling the supply of gas to the flame, an air-chamber having placement to be influenced by the heat of the flame, an interposed chamber, a connection between said interposed chamber and said air-chamber, a piston contained in said interposed chamber, a connection between said piston and said gas-controlling valve, the said piston being so combined with said interposed chamber as to be exposed on one side to the pressure within said air-chamber and on the other side to that of the atmosphere, and means permitting of the escape of air from said air-chamber and allowing its return, substantially as and for the purposes set forth.
